UNITED STATES PATENT OFFICE.

VALENTINE HOFFMAN, OF CHICAGO, ILLINOIS, ASSIGNOR OF ONE-FOURTH TO SELZ,
SCHWAB & COMPANY, OF CHICAGO, ILLINOIS, A CORPORATION OF ILLINOIS.

CONTROLLER FOR SHOE MACHINERY.

1,103,204.

Specification of Letters Patent. Patented July 14, 1914.

Application filed July 31, 1911. Serial No. 641,447.

To all whom it may concern:

Be it known that I, VALENTINE HOFFMAN, a citizen of the United States, residing at Chicago, in the county of Cook and State 5 of Illinois, have invented certain new and useful Improvements in Controllers for Shoe Machinery, of which the following is a specification, reference being had therein to the accompanying drawing.

10 My invention relates to controllers for shoe machinery; its primary object is to provide an automatic starter requiring for its operation pressure by the operator in carrying on his work as in crowding the 15 material on the last, and its secondary object is to provide an automatic stop-device.

The invention consists in the matters hereinafter described and then pointed out in the claims.

20 In the accompanying drawing which illustrates a practical embodiment of my invention:—Figure 1 is a front view of a tacking machine embodying my invention; Fig. 2 is a side view of the same; Fig. 3 is a side view of parts of the mechanism on a larger scale; Fig. 4 is a top plan view of parts shown in Fig. 3; Fig. 5 is a detail cross-sectional view on the line 5—5 of Fig. 3; Fig. 6 is a detail side view of 30 parts of Fig. 3 in their second positions; Fig. 7 is a view partly in section and partly in front elevation of parts shown in Fig. 6; Fig. 8 is cross-sectional view partly in elevation of certain parts shown in Fig. 6, 35 and Figs. 9 and 10 are detail views of a form of clutch conveniently employed.

In the drawings the numeral 20 represents a suitable column upon which a table 21 is supported. The table is provided with 40 any suitable tacker mechanism; in the present embodiment a tacker and joiner for the inner seam between the uppers and welts of shoes is shown, it being understood that the mechanism of the shoe-machinery may 45 be varied without departing from my invention. In the form shown the table carries a head or upright 22 having a forwardly projecting arm 23 which is provided at its front end with a laterally projecting wing 50 24, to support certain parts of the shoe-mechanism.

A drive shaft 25 is journaled in suitable bearings 26 on brackets 27 and is provided with a loose drive pulley 28 to which power 55 is applied from any suitable source. The

shaft 25 carries a sheave 29 near one end from which a belt 30 transmits motion to a wheel 31 of a tack-hopper 32 mounted on a stud in the end of the lateral arm 24 feeding the tacks in any suitable manner 60 now well-known in the art to a race-way 33 having a lid 34 and leading to a tack-separating device 35 having a nozzle 36, the way having a knocking-lever 37 operated by a projection 38 on a driving-bar 65 39. The driving bar reciprocates in a guide 40 on the front end of the arm 23; its lower end carries a driver 41 moving in the nozzle 36, and its upper end is connected to the forwardly projecting arm 42 of a bell-crank driving-lever pivoted at 43 to a bracket on the head and having a lever-spring 44 wound under tension on its pivot and bearing upon the arm 42 as shown in Fig. 2. The free end 45 of the driving 70 lever projects into the path of a cam 46 on the shaft 25 whose movement puts the lever-spring under tension to operate the driving-lever when the cam passes out of engagement with the latter; normally the 75 free end of arm 45 rests in a depression 46' in the cam. The shaft 25 carries an eccentric 47 and an eccentric strap 48 which operate a separator 49 for the tacks in a manner now well understood in the art. 80 The shaft 25 and the driving pulley 28 may be coupled by any suitable clutch; the one now about to be described is typical in this respect and has been practically used. The shaft 25 carries a clutch-hub 50 keyed 85 to the shaft as shown in Fig. 10. The hub 50 thereon as at 51 and having a flange 52 and held against lateral displacement by one of the bearings 26 and a collar 53 pinned to the shaft as shown in Fig. 10.

The hub 50 fits into and receives the 95 sleeve 54 of a clutch-tumbler which is provided with a plurality of longitudinal channels to receive rollers 55 which are of greater diameter than the depth of the channels or thickness of the sleeve 54 and normally rest in recesses or grooves 56 cut in the periphery of the hub and out of contact with the barrel 57 of the loose pulley 28 and so that the pulley may freely revolve on the shaft under normal conditions but 100 when the hub and sleeve are moved relatively to each other the rollers will be cammed up against the barrel of the pulley 28 to clutch or lock the shaft and pulley 105 together to drive the former.

The sleeve 54 of the clutch-tumbler is provided with an eccentric enlargement or head 58 provided with a laterally opening recess to receive a coiled spring 59 which is attached at its ends to the head 58 of the tumbler and to the flange 52 of the hub 50, respectively, and the head is provided with a stop-tooth 60 which is engaged by a detent or clutch-lever 61 mounted on a rock-shaft 62 journaled in bearings in the head and in one of the brackets 27. When the detent is in engagement with the stop-tooth 60, the spring 59 is expanded and the parts 50 and 54 are so related that the rollers 55 lie in the grooves 56 and do not act on the barrel 57 of the pulley 28; when the detent is withdrawn the pulling force of the spring moves the sleeve 54 around on the hub 50 and this forces the rollers 55 into engagement with the barrel 57 and hub 50 to clutch these parts together to revolve the shaft 25 to which the hub is splined. When the detent returns into engagement with the stop 60 the tumbler 54 stops and the momentum of the machine expands the spring 59 to restore its tension.

A supporting arm 63 is bolted to the table 21 and at its outer end is bent or curved upwardly as at 64 and extended forwardly in line with the tack nozzle 36, terminating slightly in the rear thereof, all as clearly shown in Figs. 1 and 2. This arm carries a gage-slide 65 mounted in suitable guides 66 and held in its forward position shown in Fig. 3 by a spring 67 secured at its ends to the slide and head, respectively. The rear end of the arm 63 is provided with a pair of front and rear posts or uprights 68 and 69, the post 68 having a spring 70 coiled about it and the post 69 having a collar 71 secured to it. A sliding block 72 is provided with elongated slots to receive the posts and is supported in sliding and pivotal position thereon by the spring and collar 45 in line with the slide 65. The block 72 carries a lateral pin 73 which engages an elongated slot 74 in an angularly depending arm 75 fast on the shaft 62 so that as the block moves rearwardly under the impulse of the slide 65 it will rock the shaft to withdraw the detent 61 from the stop-tooth 60 and as it moves forwardly under the pull of its spring 76 will return the detent into the path of the tooth, the spring 76 being secured at 55 one end to the post 68 to return the block to its normal forward position. The arm 63 is provided with a depending bracket 77 which carries an upright 78 made hollow at its upper end to receive a coil spring 79 and a movable post 80 resting on the spring and carrying an anti-friction roller 81 at its upper end in the path of the cam 46. The post 80 carries a lateral pin 82 which takes over and engages the front end of the block 65 72 to depress its front end to tilt the block

as shown in Fig. 6 when the post is depressed against the tension of its spring 79 by the cam. The forward end of the slide 65 carries a pin 83 which engages an adjustable set-screw 84 in the arm 63 to vary the extent 70 of its movement, and also a curved wing or gage 85 in the line of tacks and against which the work is pressed, and its rear end is beveled as at 86 in order to allow the front end of the block to freely move 75 under it and return to position in alignment with it.

In using the machine the operator is required to press the last and material against the gage or plate in order to operate the machine. When pressure is thus applied to the gage 85 the slide 65 is pushed rearwardly and pushes the block 72 in the same direction so that pin 73 turns shaft 62 to throw the detent 61 out of the path of the stop 60. The spring 59 now moves the sleeve 54 and forces the rollers 55 out of the grooves 56 of the hub 50 and clutches the hub and pulley together to revolve the shaft 25. As the shaft 25 revolves in the direction of the arrow in Figs. 3 and 9 its cam 46 begins to raise the arms 45 which rested in the depression 46' in the face of the cam, and places the spring 44 under tension; when the cam completes about one-half of a revolution it begins to act on roller 81 to depress the post 80 and front end of the block 72 when the spring 76 pulls the front end of the block under the bevel 86 as shown in Fig. 6 which movement allows the arm 75 to rock 100 back to position to again throw the detent into the path of revolving stop. The continued revolution of the shaft operates the tack-separator and allows the arm 45 to drop off into the recess 46'' when the spring 44 105 operates the driving-lever and driver to drive the tack. When that is done the stop 60 comes against the detent 61 and the parts are restored to the position of Fig. 9. By this means the clutch cannot be tripped or 110 operated and the machine cannot make its stroke unless the operator exerts a pressure on the slide 65, and as he exerts this pressure by applying the last and its material to the gage or wing 85 be necessarily crowded 115 the material upon the last as the last is presented with its bottom or sole to the tack and the material extends more or less upon the sole in order to be tacked to it. Also, as the spring 76 draws the block 72 forward 120 under the slide 65, the block and its pin 73 acting on the arm 75 throw the detent 61 up into the path of the stop 60 and stops the machine after the shaft has made its revolution, so that the machine is automatically stopped and a second stroke cannot occur until pressure is again exerted on the wing or gage-plate.

The slip-joint between the slide and block enables the spring 76 to move the block to 130

stop the machine, even if the pressure on the slide be maintained, so that the operator cannot cause a second stroke even if he fails to promptly remove the pressure of the last. 5 When the pressure is taken off the slide 65 its spring 67 draws it forward so that the block 72 can return to position; the tension of spring 67 may be varied to require different degrees of pressure to operate the 10 machine, and the gage or wing of the slide may be variably positioned with respect to the tack-nozzle by a stop 87 on the slide engaging one of the guides 66 and adjusted by any suitable means such as the slot 88 15 and bolt 89 with the slide. By employing means requiring the pressure of the shoe- last in the hand of the operator upon the gage-plate or wing to start the machine the operator necessarily must crowd the mate- 20 rial to its place on the last; by having an automatic throw off or stop-device the machine can make but a single stroke until this pressure is removed and the parts have returned to normal position. 25 It is obvious that the machine may be used as a gang-tacker by causing the driving-lever to drive a plurality of tack-drivers or driving-bars by duplicating these latter parts and their associated accessories. Also, 30 various forms of clutch may be employed, and the details of the starting and stopping mechanisms may be varied without departing from the scope of my invention.

I claim:—

35 1. In a machine of the class described, tack-driving mechanism, a power shaft therefor, a clutch to couple and uncouple the same, clutch-operating mechanism comprising a pair of movable elements having 40 a slip-joint and adapted to be moved to couple the clutch by the movement of the shoe-material into the line of the tack-nozzle, cam-actuated means to move one of the elements to break the joint with the 45 other, and a spring to retract said cam-actuated element to uncouple the clutch.

2. In a shoe-tacking machine, tack-driving mechanism, a power shaft therefor, a clutch to couple and uncouple the same,

clutch-operating mechanism comprising a 50 movable slide and a pivoted sliding block having a slip-joint and adapted to be moved together in one direction to couple the clutch by the pressure of the shoe-material thereon when the latter is moved into the line of the 55 tack-nozzle, a spring for the block, cam-actuated means to move the block to break the joint between the slide and block, and a spring to reversely move the block to uncouple the clutch. 60

3. A shoe-tacking machine, tack-driving mechanism, a power shaft having an actuating cam therefor, a clutch to couple and uncouple the same, a clutch-controlling element, a rock-shaft carrying said element, a 65 slide normally in the line of the tack-nozzle and adapted to be moved by the movement of the shoe-material into position to receive the tacks, a pair of posts in rear of the slide, a block slidably and pivotally supported on 70 the posts normally in the path of the slide, a pin on the block, an arm on the rock-shaft having a slot for the pin, a post in the path of the cam having a pin to move the block on its pivot, and means to return the 75 block to normal position.

4. In a shoe-tacking machine, tack-driving mechanism, a power shaft having an actuating cam therefor, a clutch to couple and uncouple the same, a detent to control the 80 clutch, a rock-shaft carrying the detent, a slide and block having a slip-joint and adapted to be moved together in one direction by the movement of the shoe-material into position to be tacked, posts on which 85 the block is slidably and pivotally mounted, an arm on the rock-shaft having a pin and slot connection with the block, a post in the path of the cam to move the block on its pivot, and springs to return the slide and 90 block to normal position when pressure is removed from the slide.

In testimony whereof I affix my signature in presence of two witnesses.

VALENTINE HOFFMAN.
